UNITED STATES PATENT OFFICE.

WILLIAM A. WALES, OF PLAINVILLE, CONNECTICUT, ASSIGNOR TO ALLISON N. CLARK, OF SAME PLACE.

CHECK-REIN FASTENER.

SPECIFICATION forming part of Letters Patent No. 320,728, dated June 23, 1885.

Application filed February 25 1885. (No model.)

To all whom it may concern:

Be it known that I, WILLIAM A. WALES, a citizen of the United States, residing at Plainville, in the county of Hartford and State of Connecticut, have invented certain new and useful Improvements in Check-Rein Fasteners, of which the following is a specification.

In the accompanying sheet of drawings, Figure 1 is a plan view of my check-rein fastener or holder together with an ordinary check-hook. Fig. 2 is a side elevation of the same. Fig. 3 is a transverse section of my said holder on line $x-x$ of Fig. 1.

A is an ordinary check-hook. My holder is designed to be attached to a check-rein for securing the rein to the check-hook.

B designates the frame of my holder, in the rear end of which is formed the eye a to slip over the check-hook A, and at the opposite end of said frame is a loop or eye for attachment of the check-rein C.

Upon the end of the frame having the eye a, and practically forming one side of said eye, is the sliding follower b of rigid material, and back of said follower is a stiff metallic spring, c, which presses against the follower with a constant tendency to press it toward the rear side of the eye a. I prefer to make this follower of sheet metal bent over and around the two sides of the frame, and with a block of wood or leather inclosed inside of the frame, as shown and secured by rivets.

When the holder is placed upon the check-hook the follower b is pressed against the front side of the check-hook with all the force of the metal spring c. The rigid follower may have a leather pad or cushion at the end which faces the check-hook provided said

leather projects but a slight distance from the metal portion of the follower, so that the check-hook cannot embed itself in the follower to any considerable extent. This holder will secure the check-rein upon the check-hook so firmly as to make it impossible for even the most uneasy horse to detach the holder therefrom.

If desired, instead of a sheet-metal spring one or more spiral springs may be used to force the follower toward the check-hook.

I am aware that soft rubber has been secured within the eye of check-rein holders or fasteners in order to better secure them upon the check-hook; but the rubber is so soft and easily indented to a considerable depth that horses will easily unhook the fastener.

I am also aware that a prior patent shows a check-rein holder having a loop to receive the check-rein and a loop to receive the ordinary check-hook, the latter loop being provided with a sheet-metal spring, one end of which presses directly upon the check-hook to hold the device in place. All of said prior art is hereby disclaimed.

I claim as my invention—

The herein-described check-rein fastener consisting of the frame B, having the eye a at one end, the follower b, mounted to slide thereon, and a metal spring acting against said follower to force it toward the rear side of said eye, substantially as described, and for the purpose specified.

WILLIAM A. WALES.
